X-RAY CHANGE OVER SYSTEM

Montford Morrison, Montclair, N. J., and Stanley E. Lundquist, Jackson Heights, N. Y., assignors to Westinghouse X-Ray Company Inc., a corporation of Delaware

Application May 7, 1932. Serial No. 609,804

5 Claims. (Cl. 250—34)

Our invention relates to X-ray systems and particularly to such systems adapted for radiographic and fluoroscopic examinations. Systems of this general type are usually employed with X-ray apparatus known to the art as serialographs. This type of apparatus is usually employed by the Roentgenologist for making fluoroscopic examinations and it frequently happens that during such an examination some particular phenomenon is observed of which a radiographic picture is immediately desired. Under these circumstances the Roentgenologist immediately desires to convert the apparatus from one condition of operation to the other as expeditiously as possible.

The energy supplied to the X-ray tube for purposes of fluoroscopy examination are much less than that required for the taking of radiographic pictures, and it therefore becomes necessary to increase the energy supplied to the X-ray tube in order to convert the apparatus. This conversion usually requires a short period of time to allow the X-ray tube to be supplied with this increased energy.

Heretofore in the art the Roentgenologist has usually had to wait a short period of time before taking the radiographic picture and during this short period the particular phenomenon which it is desired to photograph may have changed in some manner.

It is, therefore, an object of our invention to provide an X-ray system which may be converted from a system utilized for fluoroscopy to a system for radiographic purposes without the necessity for waiting for the inherent change in the apparatus.

Another object of our invention is to provide a system normally employed for fluoroscopic purposes which may be converted, to a system for radiographic purposes by the Roentgenologist, automatically in response to the usual manual operation of the apparatus.

A further object of our invention is to provide a system normally employed for fluoroscopic purposes which may be converted to a system for radiographic purposes by the Roentgenologist in response to the usual manual operation of the various parts without the necessity for an undue delay in the conversion of the system.

Still further objects of our invention will become apparent to those skilled in the art by reference to the accompanying drawing wherein the single figure is a diagrammatical representation of a system for making fluoroscopic and radiographic examinations in accordance with our

invention and which may be readily converted from one condition of operation to the other.

Referring now to the drawing in detail we have shown an X-ray tube 5, which is energized by the secondary winding 6 of a high tension 60 transformer 7, the secondary winding 6 being connected to the X-ray tube by means of conductors 8 and 9. The thermionic cathode of the X-ray tube receives heating current from a low tension transformer 10, the secondary 11 of which is 65 connected to the cathode by means of the common conductor 9 and a conductor 12. The primary winding 13 of the high tension transformer 7 is arranged to receive energy from a suitable source of alternating current of usual commercial potential, such as a generator 14, through a pair of conductors L1 and L2.

A switch C is connected in series with the conductor L2 for the purposes of opening and closing the circuit to the primary winding 13 and a suitable resistance 15 is imposed in the conductor L2 and is thus in series with the primary winding 13 and the source of supply 14, for a purpose to be hereinafter more fully stated.

The primary winding 16 of the cathode heating 80 transformer 10 has one of its ends connected by means of a conductor 17 to the conductor L1 through the medium of a suitable switch D and the remaining end of this primary winding is connected to the conductor L2 by means of the 85 conductor 18 with a resistance element 19 imposed therein in the same manner as previously referred to relative to the resistance element 15.

With this portion of our system thus far described it can be readily appreciated that upon 90 closure of the switch D, the primary winding 16 of the low tension transformer 10 will become energized inducing a current in the secondary winding 11, and thus heat the cathode of the X-ray tube 5 to thermionic emission through the 95 conductors 9 and 12. Also upon closure of the switch C the primary winding 13 of the high tension transformer 7 will likewise become energized and induce a current in the secondary winding 6 which is transmitted to the electrodes of the 100 X-ray tube through the conductors 8 and 9.

The energy in flowing from the source to the primary windings 13 and 16 of the respective transformers 7 and 10 likewise flows through the 105 respective resistance elements 15 and 19. This limits the energy supplied by the source 14, through conductors L1 and L2, to each of the high and low tension transformers.

The arrangement thus far described constitutes 110

the normal circuit employed for the purposes of fluoroscopic examinations in that the energy supplied to the tube is considerably reduced by the resistance elements 15 and 19. Our system will 5 now be described when converted for radiographic purposes.

In the usual operation of any apparatus for the taking of radiographic pictures a timing device is 10 normally employed which regulates the period of energization of the X-ray tube. Such devices are well known in the art and as the same per se forms no part of our present invention we have shown 15 only diagrammatically such a timing device at 22. This device is connected in series with the conductor L2 extending from the source 14 to the primary winding 13 and is short circuited by closure 20 of the switch C for the purposes of fluoroscopy, in the manner previously described, but is actively in the circuit when the switch C is open for the purpose of radiography.

A hand switch E in the form of a push button, 25 well known to the art, is connected to the timing mechanism 22 by means of a pair of conductors 23 and 24 for the purposes of controlling operation of the timing mechanism for the time periods for which the mechanism has been preset. Normally 30 this hand switch E is supported by a support or bracket 25 when the apparatus is being employed for fluoroscopic purposes and the hand switch C is closed. This support or bracket 25 protrudes from a suitable housing 26 and is pivoted thereto at 27.

The inwardly disposed portion thereof is provided with suitable conducting surfaces 28 and 29 35 insulated from each other by a suitable insulated section 30 and from the casing by a similar insulated section, such as shown at 32.

The conducting surface 28 is arranged to engage a pair of contact members 33 and 34 and in 40 a similar manner the contact surface 29 engages contact terminals 35 and 36. When the hand switch E is placed upon the support 25, during fluoroscopic examinations, the latter is caused to slightly rotate about the pivot 27, due to the 45 weight of the hand switch E, in the direction indicated by the arrow in the figure, against the tension of a suitable coil spring 37.

A conductor 38 extends from the supply conductor L2 to the contact terminal 36 and a similar conductor 39 likewise extends from the conductor L2 to the contact terminal 35, but it is to be noted that these two conductors are connected on opposite sides of the resistance element 15.

In a similar manner a conductor 40 extends 50 from one end of the resistance element 19 to the contact terminal 34 and a conductor 42 extends from the opposite end of the resistance element 19 to the contact terminal 33.

When the apparatus is employed for fluoroscopy purposes with the hand switch E in position 60 upon the support 25, and the hand switch C closed, the energy will flow from the source 14 to the primary windings of the respective transformers 7 and 8, through resistance elements 15 and 19, as previously stated, and the energy supplied thereto will thus be limited by these resistance elements.

Assuming now that during the fluoroscopic examination the Roentgenologist observes some 70 particular phenomenon which he desires to immediately radiograph he then opens the hand switch C which de-energizes the primary winding 13 of the high tension transformer 7. The time switch mechanism is usually preset for the 75 desired period of exposure and as it is connected

in series with the supply conductor L2, it performs the same function as the switch C, for the desired period of time.

The hand switch E, which controls the operation of the timing mechanism being now supported by the support or bracket 25 the conducting surfaces 28 and 29 forming a part of the latter are disengaged from the respective contact terminals 33 to 36 inclusive. The operator removes the hand switch E from the support 25 and the coil spring 37 causes clockwise rotation thereof about the pivot point 27, causing the contact surfaces 28 and 29 to engage the contact terminals 33, 34 and 35, 36.

These contact terminals being connected across the respective resistance elements 15 and 19 comprise a shunt circuit relative thereto and upon closure thereof by the conducting surfaces 28 and 29 of the support these resistance elements are immediately short circuited and are no longer connected actively with the primary windings 13 and 16 of the transformers 7 and 10. The operator then depresses the button of the hand switch E which causes operations of the time switch mechanism 22.

This in turn immediately closes the circuit from the source of supply 14 to the primary winding 13 by completing the conductivity through the conductor L2 and the X-ray tube becomes energized for the time period regulated by the timing mechanism 22. The resistance elements 15 and 19 being now short circuited have no effect on the circuits at this time which enables the maximum energy of the source 14 to be impressed upon the primary windings 13, 16, and the X-ray tube and 110 cathode.

It must, of course, be appreciated that with the type of apparatus with which our system is employed a fluorescent screen is utilized for fluoroscopic examinations and is moved out of 115 position and a sensitized film is moved into position for radiographic examinations. After energization of the tube for the time period desired the operator replaces the hand switch E upon the support 25 which again opens the connection 120 of the contact terminals 33 and 34 by the conducting surface 28, and the contact terminals 35 and 36 by the conducting surface 29. The system, therefore, is again converted and ready for 125 operation for purposes of fluoroscopic examinations by closure of the switch C.

It can thus be appreciated by those skilled in the art that we have provided a novel arrangement of an X-ray system which may be employed for fluoroscopy or radiographic examinations and 130 which may be readily converted from one type of operation to the other with a minute lapse of time. The time required for opening or closing of the switch C and the replacement or removal of the hand switch E from the support is of sufficient duration to enable the cathode of the X-ray tube to decrease or increase to that necessary for the particular operation desired through the action of the resistance element 19.

In a like manner the energy supplied to the 140 primary winding of the high tension transformer is increased or decreased by the operation of the support effecting the action of the resistance element 15. The increase or decrease of the energy supplied to the respective transformers is naturally transmitted to the X-ray tube and cathode thus rendering them operable for the particular examination desired.

Although we have shown and described one specific embodiment of our invention we do not 150

desire to be limited thereto as various other modifications of the same may be made without departing from the spirit and scope of the invention as set forth in the appended claims.

5. What is claimed is:

1. In an X-ray system for making radiographic and fluoroscopic examinations the combination with an X-ray tube and a source of electrical energy therefor, of means connected with said

10 source of electrical energy for limiting the energy supplied thereby to said X-ray tube for fluoroscopic examinations, a time switch connected with said source for regulating the period of energization of said X-ray tube by said source for

15 radiographic examinations, a hand switch connected to said time switch for controlling operation of the latter, and a support for said hand switch comprising a switching member connected to said first mentioned means and operable upon

20 the removal of said hand switch to render said first mentioned means inoperative to limit the energy thereby causing said X-ray tube to be energized for radiographic examinations.

2. In an X-ray system comprising means for

making fluoroscopic examinations including an X-ray tube provided with a cathode to be heated, a high tension transformer for energizing said X-ray tube, a low tension transformer for supplying heating current to the cathode of said

30 tube, resistance elements connected with each high and low tension transformer for controlling the energy supplied thereby to said X-ray tube and said cathode, and means for making radiographic pictures comprising a time switch connected with

35 said high tension transformer for controlling the period of energization of said X-ray tube by said high tension transformer, a hand switch connected with said time switch for controlling operation of the latter, and a support for said hand

40 switch comprising a switch member connected with said resistance elements for short circuiting the latter upon removal of said hand switch therefrom.

3. In an X-ray system the combination of an

45 X-ray tube provided with a cathode to be heated, a high tension transformer for energizing said X-ray tube, a low tension transformer for supplying heating current to the cathode of said

50 tube, resistance elements connected with said high and low tension transformers for limiting the energy supplied by each to said X-ray tube and cathode, respectively, for fluoroscopic purposes, a time switch connected with said high tension transformer for controlling the period of

55 energization of said X-ray tube by said high tension transformer for radiographic purposes, a hand switch connected to said time switch for controlling operation of the latter, and a support for said hand switch comprising a switch member

60 connected with each of said resistance elements and normally uneffecting the operation of the latter in limiting the energy supplied to said X-ray tube and cathode while supporting said hand switch, and operative to short circuit both of said

resistance elements to cause said X-ray tube and said cathode to be energized by the entire energy of said high and low tension transformers, respectively, for radiographic purposes upon removal of said hand switch from said support.

80

4. An X-ray system for making radiographic and fluoroscopic examinations comprising an X-ray tube provided with a heat controlled cathode, a high tension transformer connected to said cathode for supplying heating current thereto, a source of electrical energy for each of said high and low tension transformers, resistance elements connected in series with said high and low tension transformers and the respective source of electrical energy for each for limiting the supply of energy to said X-ray tube and said cathode, a time switch connected with said high tension transformer and its respective source of electrical energy for regulating the period of energization of said X-ray tube by said high tension transformer for making radiographic pictures, a hand switch connected with said time switch for controlling the operation of the latter, and a support for said hand switch comprising a switch member normally inoperative while supporting said hand switch to effect said resistance elements in series with said high and low tension transformers to enable the latter to energize said X-ray tube and said cathode for purposes of fluoroscopic examinations, and said supporting switch member being operable upon removal of said hand switch to short circuit said resistance elements to cause said X-ray tube and cathode to be energized for radiographic purposes.

85

5. In an X-ray system for making radiographic and fluoroscopic examinations the combination with an X-ray tube provided with a cathode to be heated and a source of electrical energy for said tube and cathode of resistance elements connected with the source of electrical energy for said

90

tube and cathode, for limiting the energy supplied thereto for fluoroscopic examinations, a time switch connected with the source of energy for said tube for regulating the period of energization of the latter for radiographic examinations, a hand switch for controlling the operation of said

95

time switch, and supporting means for said hand switch comprising a pivoted switch member arranged to engage a plurality of contact terminals connected to said resistance elements, said supporting means being adapted to rotate about its pivot to disengage said contact terminals when said hand switch is placed thereupon to render said resistance elements operative to limit the energy supplied to said tube for fluoroscopic ex-

100

aminations, and said supporting means being adapted to rotate about its pivot and engage said contact terminals when said hand switch is removed therefrom to render said resistance elements inoperative to limit the energy thereby causing said X-ray tube and cathode to be energized for radiographic purposes.

105

6. In an X-ray system for making radiographic and fluoroscopic examinations the combination with an X-ray tube provided with a cathode to be heated and a source of electrical energy for said tube and cathode of resistance elements connected with the source of electrical energy for said

110

tube and cathode, for limiting the energy supplied thereto for fluoroscopic examinations, a time switch connected with the source of energy for said tube for regulating the period of energization of the latter for radiographic examinations, a hand switch for controlling the operation of said

115

time switch, and supporting means for said hand switch comprising a pivoted switch member arranged to engage a plurality of contact terminals connected to said resistance elements, said supporting means being adapted to rotate about its pivot to disengage said contact terminals when said hand switch is placed thereupon to render said resistance elements operative to limit the energy supplied to said tube for fluoroscopic ex-

120

aminations, and said supporting means being adapted to rotate about its pivot and engage said contact terminals when said hand switch is removed therefrom to render said resistance elements inoperative to limit the energy thereby causing said X-ray tube and cathode to be energized for radiographic purposes.
